UNITED STATES PATENT OFFICE.

EARNEST A. EASTMAN, OF DAYTON, OHIO, ASSIGNEE OF ONE-HALF TO THE CRAWFORD
McGREGOR AND CANBY CO., OF DAYTON, OHIO, A CORPORATION OF OHIO.

LAST-TURNING MACHINE.

1,104,040.

Specification of Letters Patent. Patented July 21, 1914.

Application filed March 20, 1913. Serial No. 755,667.

To all whom it may concern:

Be it known that I, EARNEST A. EASTMAN, citizen of the United States, residing at Dayton, in the county of Montgomery and State of Ohio, have invented certain new and useful Improvements in Last-Turning Machines, of which the following is a specification:

My invention relates to wood turning machines and particularly to lathes for turning irregular shapes.

The machine herein described is especially adapted for turning shoe lasts, heads for golf sticks, gun stocks and other articles of similar, irregular formations.

The object of the invention is to simplify the structure as well as the means and mode of operation of such machines, whereby they will not only be cheapened in construction but will be more efficient in use, automatic in their action, easily and quickly adjusted and unlikely to get out of repair.

Since lasts of the extreme shapes necessary to meet the requirements in manufacturing shoes of the present styles, termed in the trade as thin comb lasts, have the curvatures on each side of the last so pronounced that the ordinary last turning machines can not produce such curves.

One of the primary objects of the present invention is to provide a machine by which lasts embodying such extreme curvatures may be automatically turned with great accuracy necessary to meet the demands of the trade. To accomplish this

there must be employed a cutter head of sufficiently small size to enter and follow the lines of such curvatures. The last block from which the finished product is to be turned, is necessarily much larger than the last to be produced to allow for the extreme type of comb. This last block of great size necessitates in certain parts very deep cuts, which are found to be too great for the small cutter head, which is necessary to produce the extreme curvatures required. In order that it shall not be necessary to operate the small cutter head to produce a cut of the extreme depth, which when the small cutter is at its extreme depth in the curve, might cause it to back cut or cut across the center, thereby either stopping the cutter head or perhaps breaking the cutter and spoiling the work, it has become the custom to take a

preliminary cut from the last block by means of a roughing cutter. This necessitates two separate operations. First the roughing of the last block by means of a larger cutter head and then the returning or the finishing cut taken by the smaller cutter head. These operations are usually performed upon separate machines thereby involving increased expense and labor.

A further object of the invention is to provide a turning machine in which both heads are combined and work simultaneously, the roughing cutter operating slightly in advance of the finishing cutter. Inasmuch as the finishing cutter is directly controlled by the master form, it has heretofore been found when attempting to employ a roughing cutter and a finishing cutter upon the same machine, that as the finishing cutter enters one of the recesses of extreme curvature, the roughing cutter in advance thereof, was equally permitted to make a cut of too great depth. This particularly occurs at the time the finishing cutter is operating upon the curvature across the toe of the last, at which time the roughing cutter if operating too far in advance of the finishing cutter, will cut too deeply into the comb of the last, thereby destroying the finished product. To obviate this, it has been found necessary to operate the cutter heads very closely one to the other. To provide such a construction, whereby this difficulty is overcome, is one of the objects of the invention.

With the above primary and other incidental objects in view, as will more fully appear in the specification, the invention consists of the features of construction and their combinations thereof and the mode of operation or their equivalents, as herein after described and set forth in the claims.

Referring to the drawings, Figure 1 is a front elevation of a shoe last turning machine, embodying the invention. Fig. 2 is a detail plan view of the last turning machine with the upper structure removed. Figs. 3 and 4 are a side elevation and a transverse sectional view respectively illustrating the driving connections of the cutter heads. Figs. 5 and 6 are detail end elevations and plan views respectively, of the cutter heads. Fig. 7, 8 and 9 illustrate a modification of the driving means.

Like parts are indicated by similar characters of reference throughout the several views.

While the present invention relates primarily to the cutter heads in their relation one with the other, together with their driving connections, in order to illustrate the application of the invention and its relation to other portions of the apparatus and the method of operation, there has been shown in the drawings a last turning machine of a type commonly employed, to which the invention has been applied. This last turning machine comprises a bed portion 1 supported upon legs 2 and from which projects upright standards 3 connected one with the other and suitably braced to form a rigid, main frame.

Pivots supported upon forward extending arms 4, carried by the upright standards 3, is a swinging frame comprising pendant arms 5 connected by transverse bars 6 and suitably braced into a rigid structure, which is free to oscillate forward and rearward about its pivotal connections 7. Carried upon suitable trunnions, journaled in bearing bars 8, is the revolute master form 9. The drive trunnion of the master form, carries a gear pinion 10, meshing with a corresponding pinion 11, upon a counter shaft 12. This counter shaft 12 carries a second pinion 13 meshing with a corresponding pinion 14, upon the drive spindle or trunnion 15, with which is engaged with the last block or other work to be operated upon. The counter shaft 12 carries at its extremity a pulley 17, connected by a belt 18 with a counter shaft 19, operatively connected through sundry belts and counter shafts 40 with the main drive shaft 20 journaled in the lower part of the main frame. By the rotation of the main drive shaft 20, the counter shaft 12 is rotated to revolve the master form 9 and the work 16 in unison. 45 This revoluble movement of the master form and work continues at a uniform rate, regardless of the oscillatory movement of the swinging frame.

Slidingly mounted to reciprocate upon the bed 1, is a sliding head 21, carrying a master or guide wheel 22, engaging the master form 9, and a second sliding head 23, carrying the cutter heads, which form the subject matter hereof and which operate upon the work 16, journaled in the swinging frame and rotated by the counter shaft 12. These sliding heads 21 and 23 move in unison under the influence of feed devices 24.

The swinging frame at all times tends to move inward which movement is arrested by the engagement of the master form 9 with the guide or master wheel 22. As the master form 9 is rotated, the portions thereof at greater or less distances from the axis, brought into engagement with the master

or guide wheel, causes the swinging frame to oscillate to shift the work 16 to or from the cutter heads, causing said cutter heads to operate at greater or less depth in the last block or rough stock.

The sliding movement of the heads 21 and 23, causes the master wheel or guide wheel 22 to successively engage every portion of the master form 9, the cutter heads being moved in unison with the master or guide wheel 22, are caused to operate upon every portion of the block or rough stock, whereby there is produced a finished product which is the counter part of the master form 9. This is the usual construction and operation of turning machines of this type, and in itself forms no part of the present invention.

Journaled in suitable uprights or standards 24, carried by the head 23, are two parallel shafts 25 and 26. Upon the shaft 26 there is carried a head 27, provided with a plurality of curved or spoon shaped cutter blades 28. These blades 28 are removably carried in the head 27 and may be disengaged for sharpening, repairs or replacement. This head 27 and its cutting blade 28, comprises the roughing or advance cutter. Carried upon the shaft 25 is the finishing cutter head comprising a plurality of semi-circular blades 29, the curvature of these blades and the diameter of the finishing head corresponds with the external dimensions of the master or guide wheel 22.

As shown in Figs. 2 and 6, the finishing cutter head is set as close to the working line of the roughing cutter head as is practical. In actual practice it has been found feasible to operate the roughing cutter head 27 a distance of substantially one sixteenth of an inch in advance of the finishing head. The impact of the cutting blades breaks the material through the intervening one sixteenth of an inch space, causing the path of operation of the large cutter head to merge into that of the small cutter head, made simultaneously therewith. This roughing cutter head blades 28 are preferably of different lengths, each succeeding blade about the periphery of the heads being of slightly greater length than the preceding blade, whereby each succeeding blade will cut slightly deeper into the work. It is to be noted that the shafts 25 and 26 are arranged at an inclination to the axis of rotation of the work. The oscillation of the work to and from the cutter head is in accordance with the cut to be made by the finishing head regardless of the roughing cutter. If the roughing cutter is set too far ahead of the finishing cutter it will destroy the work by cutting too deeply into portions of the block where a shallow cut should be taken. This is due to the fact that the depth of operation of the roughing head is controlled in unison with the cut of the

finishing head. By arranging the heads side by side, as shown in the drawings, and so related one with the other, as to permit their operating points to be closely adjacent, this difficulty is obviated. It is to be understood that the cutter heads are moved parallel with the axis of rotation of the work. This is accomplished by the shifting movement of the sliding carrier head 23 before mentioned. The finishing head and the roughing cutter head are rotated at different rates of speed. In practice it has been found most desirable to rotate the roughing cutter head at the rate of approximately six thousand revolutions per minute, while the finishing cutter head rotates at an approximate speed of ten thousand revolutions per minute. To maintain an operative driving engagement, by which these cutter heads will be rotated at constant rates of speed throughout their longitudinal movement, there is provided upon the drive shaft 20 a drum 30, over which passes a belt 31, driving a pulley 32 upon a shaft 33, mounted in bearings 34, upon the sliding carrier 23. This shaft 33 is arranged at an angle with the axis of the rotation of the work and coincide with the inclination of the cutter head shafts 25 and 26. On account of the great difference of the diameters of the driving drum 30 and the driven pulley 32 and the variation or inclination of the axis of the shaft 33 with the drive shaft 20, in order to maintain operative engagement between the belt 31 and the pulley 33, there are provided on opposite sides of the pulley 33, idle pulleys 35 and 36. The shaft 33 carries two pulleys 37 and 38 connected by belts 39 and 40, with corresponding pulleys upon the cutter head shafts 25 and 26 respectively. Thus both cutter head shafts are driven from the same counter shaft 33, the difference in the rate of rotation being due to variations in the relative sizes of the pulleys carried by such said shafts 33, 25 and 26. As the carrier head 23 is shifted longitudinally, the belt 31 will move therewith, engaging successively different portions of the drum 30.

In the modification of the driving connection as illustrated in Figs. 7, 8 and 9, the counter shaft 33 and its pulleys are omitted from the sliding head 23 and the driving drum 30 is belted direct to the pulley 41 upon the cutter head shaft 26. On account of the great variation in the diameter of the drive drum 30 and the pulley 41, idler pulleys 42 and 43 are provided to insure operative engagement between the driving belt and the pulley 41. In this construction the cutter head shaft 26 carries at its extremity a pulley 44, while the shaft 25 is provided with a similar pulley 45. A driving belt 46 operatively engages the pulleys 44 and 45, passing over the idler pulleys 47 and 48 intermediate said pulleys 44 and 45 to insure the operative engagement of the belt with said pulleys. The pulleys 41, 44 and 45 are proportioned in relation one with the other and with the driving drum 30, whereby the desired relative speed of rotation of the shafts 25 and 26 is attained. The small or finishing cutter head may be of any desired construction. The preferred form of cutter, however, comprises a rectangular head, having oppositely disposed beveled edges to the alternate beveled faces of which are attached the semi-circular cutting blades 29.

By the construction herein described, the roughing cutter head removes the surplus stock to an approximate form slightly in advance of the finishing cutter head, which reduces the approximate form to a shape corresponding exactly with the master form. The two cutter heads operating in planes so closely adjacent, one with the other, are capable of being controlled by the master or guide wheel common to both the cutter heads, which is not permissible when the cutter heads operate in more widely separated planes.

From the above description it will be apparent that there is thus provided a device of the character described, possessing the particular features of advantage before enumerated as desirable, but which obviously is susceptible of modification in its form, proportion, detail construction or arrangement of parts, without departing from the principle involved or sacrificing any of its advantages.

While in order to comply with the statute, the invention has been described in language more or less specific as to certain structural features, it is to be understood that the invention is not limited to any specific details, but that the means and construction herein described comprise but one mode of putting the invention into effect, and the invention is therefore claimed broadly in any of its possible forms or modifications within the scope of the appended claims.

Having thus described my invention, I claim,

1. In a wood working machine, a support for the work to be operated upon, a traveling head, two parallel shafts carried by the head and arranged at an inclination to the direction of travel of the head, cutter heads of different diameters carried by said shafts and rotating in parallel adjacent planes, the larger of the heads being located slightly in advance of the smaller head, and means to rotate the heads.
2. In a wood working machine, a support for the work, a traveling head, two revoluble cutter heads carried by the traveling head and rotating in parallel adjacent planes inclined in relation with the path of travel of

the head, the relative positions of the cutter heads being such that the inoperative side of the rearmost cutter head or the side opposite the cutting point will extend beyond the cutting point of the advance head, and means to rotate the cutter heads.

3. In a wood working machine, a support for the work, a traveling head, two revoluble cutter heads carried by said traveling head 10 and rotating in parallel planes, the advance head being of greater diameter than the follower head, the relative location of the heads being such that the path of operation of the larger head will merge into the path 15 of operation of the smaller head formed simultaneously therewith.

4. In a wood working machine, a support for the work, a traveling head, two eccentrically mounted revoluble cutter heads carried by the traveling head and rotating in parallel planes the heads being so located in relation one with the other, that the simultaneous paths of operation of the two cutters will merge one into the other.

5. In a wood working machine, a support for the work, a traveling head, two cutter heads carried thereby rotating at different rates of speed in parallel planes inclined to the path of travel of the traveling head, the 30 planes of rotation of the heads being so relatively located that the path of operation of one head will merge into the simultaneous path of operation of the other head.

6. In a last turning machine, the combination of a frame, a laterally movable support for the model and work, a longitudinally movable carriage, a pair of shafts mounted on the carriage at an oblique angle to the line of the bearings of said work, a cutter 35 head on each shaft, means to revolve said shafts in the same direction, radial blades mounted on the outer cutter head and extending across the central line of the inner

cutter head, and curved blades mounted on the inner head to engage the work in different planes longitudinally of the axis of the work.

7. In a last turning machine, the combination of a frame, a laterally movable support for the model and the work, a longitudinally movable slide mounted on the frame, a pair of parallel shafts mounted on the slide at an oblique angle to the line of movement of their support and of the movement of the work support, a cutter head mounted on each shaft, a series of cutter blades mounted on each head, the blades of each head forming steps, and the blades of one head extending across the central line of the shaft of the other head.

8. In a last turning machine, the combination of a frame, a laterally movable support for the model and work, a longitudinally movable slide mounted on the frame, a pair of parallel shafts mounted on the slide in 65 the same plane with, but at an oblique angle to the line of the work, a cutter head mounted on each shaft, a series of cutter blades on each head, and means to secure said blades to said heads in such a manner that 70 each blade will engage the work in a separate transverse plane.

9. In a pattern lathe, means for rotating the work, a roughing cutter and a finishing cutter eccentrically mounted to rotate in parallel planes closely adjacent one to the other and engaging the same side of the work, said cutters being of different diameters whereby the larger cutter will project beyond the center line of the small cutter.

In testimony whereof, I have hereunto set my hand this 17th day of March, 1913.

EARNEST A. EASTMAN.
